APPARATUS FOR THE TRANSFER OF
SENSIBLE AND LATENT HEAT

Paul A. Scherer, San Francisco, Calif.

Application December 4, 1939, Serial No. 307,478

14 Claims. (Cl. 62—139)

This invention relates to heat transferring apparatus and relates more particularly to apparatus of this nature adapted for the treatment or conditioning of air, for use in fractional distillation, etc. A general object of the invention is to provide a practical, dependable, and particularly effective apparatus of this character.

Another object of this invention is to provide a multi-stage heat transferring apparatus suitable for use as an air conditioner in which there is effective latent and sensible heat transference in each stage.

Another object of this invention is to provide an apparatus of the character mentioned in which a cooling action and a drying action or dehumidifying action is carried on in two or more like or identical correspondingly positioned units, promoting economical manufacture and installation.

Another object of this invention is to provide an apparatus of the character mentioned that is effective in producing a marked reduction in the temperature of the air treated while maintaining a low humidity.

Another object of this invention is to provide an apparatus of the character mentioned in which water and brine are employed as the evaporative and absorptive mediums and flow as films on the surfaces of spaced sheets of a material that is effective in the transference of the heat by conduction, and that is substantially unaffected by the liquids. In the improved apparatus of the present invention glass sheets are utilized as the carriers for the liquid films and as heat conducting elements, the glass of the plates being effective in the conduction of the heat and being resistant to oxidation, corrosion, rot, etc.

Another object of this invention is to provide an apparatus of the character mentioned in which the plates are of unique shape or finish to assure the most effective distribution of the liquid films over the plate surfaces.

Another object of this invention is to provide an apparatus of the character mentioned embodying novel and very effective regulable control means for controlling the thickness of the liquid films on the plate surfaces to control or vary the action of the apparatus.

Another object of this invention is to provide an apparatus of the character mentioned in which the plate surfaces may be easily and quickly flushed from time to time as conditions may require, without dismantling the apparatus and without the removal of any of the parts.

Another object of this invention is to provide an apparatus of the character mentioned that is quiet in operation and that requires a minimum expenditure of power.

5 5 A further object of this invention is to provide an apparatus of the character mentioned in which outside air and continuously recirculated air are employed as the evaporative mediums, as the mediums from which the water vapor is condensed, and to some extent as the heat transferring agents.

10 10 The various objects and features of my invention will be fully understood from the following detailed description of a typical, preferred form and application of the invention, throughout which description reference is made to the accompanying drawings, in which:

15 15 Fig. 1 is an isometric perspective view of a preferred form of apparatus of the invention. Fig. 20 20 Fig. 1^a is a schematic view illustrating the action of the apparatus. Fig. 2 is an enlarged side elevation of one unit or bank of the apparatus with portions broken away to illustrate certain elements in vertical cross section. Fig. 3 is a vertical detailed sectional view taken as indicated by line 25 25 3—3 on Fig. 2. Fig. 4 is an enlarged fragmentary vertical detailed sectional view taken as indicated by line 4—4 on Fig. 3, and Figs. 5 and 6 are enlarged fragmentary horizontal detailed 30 30 sectional views taken as indicated by lines 5—5 and 6—6, respectively, on Fig. 4.

35 35 The invention may be embodied in devices or apparatus varying considerably in purpose or application, for example, it may be embodied in air conditioning apparatus, in fractional distilling apparatus, in cooling towers, etc. In the following disclosure I will describe the invention embodied in an air conditioning apparatus, it being understood that the invention is not to be considered as limited to this particular application or to the specific details herein described.

40 40 The apparatus of the present invention may be said to comprise, generally, two like units A and B each comprising a bank of spaced sheets 45 45 10 and means 11 supplying films of water and brine to the sides or surfaces of the sheets 16, means 12 for circulating the air to be treated into contact with the films of the unit A, means 13 for circulating air between the water films of the unit A and the brine films of the unit B, and means 14 for circulating outside air into contact with the water films of the unit B.

50 50 The units A and B are preferably, though not necessarily, carried by a single or common base 55 55 15. The opposite sides 16 of the base 15 have up-

standing intermediate walls 17 and similar up-standing walls 18 at each end. The base 15 includes a bottom wall provided with longitudinally spaced raised platforms 19. Liquid containers or sumps 20 are formed between the outer ends of the platforms 19 and the end walls 21 of the base 15. The space between the spaced platforms 19 is partitioned to form two liquid sumps 20. The sumps 20 are provided to receive and contain the water and brine, as will be later described.

In the preferred construction the two units A and B are alike or identical to promote economy in the manufacture, and in the present disclosure corresponding parts of the units are designated by corresponding elements. The units A and B are supported on the base platforms 19 and are partially confined by the base side walls 16, 17 and 18. Each unit A and B includes a pan 22 resting on a platform 19. The pans 22 are engaged between the sides 16 of the base 15 and have lips 23 along their upper edges bearing on the flanged upper edges of the base sides 16. Longitudinally spaced gaskets 24 are arranged transversely under the pans 22 to seal with the platforms 19 and the base sides 16 to prevent the leakage of fluid under the pans. A gasket pad 25 of rubber, or the like, rests within each pan 22.

The plates or sheets 10 are characterizing elements of the units A and B. The sheets 10 are preferably formed of glass or the equivalent, and are preferably alike or identical. Each unit A and B includes a series or bank of spaced substantially parallel sheets 10. The sheets 10 of each unit are equally spaced apart and the units A and B have an equal number of sheets. The sheets 10 are arranged vertically, that is, the broad surfaces 26 of the sheets 10 are substantially vertical and the sheets have their lower edges resting on the gasket pads 25. The sheets 10 are positioned so that their broad surfaces 26 are in vertical planes substantially parallel with the planes of the base sides 16. In the preferred construction the sheets 10 are rectangular and are proportioned to project upwardly from the base 15 to have their upper edges adjacent the upper edges of the walls 17 and 18. The outermost sheets 10 engage against or lie adjacent the sides of the pans 22 while the opposite ends of the sheets 10 are at the ends of the pans. The pads 25 form supports for the sheets 10 and the weight of the sheets is such that the lower edges of the sheets are slightly embedded in the resilient pads 25 and dependable seals are formed at the pad. The engagement of the lower edges of the sheets 10 with the pad 25 assists in holding the sheets in spaced parallel relation.

Drain plates 26 are arranged at opposite ends of the pans 22 to form the end walls of the pans. Gaskets 27 of rubber, or the like, are provided on the inner sides of the plates 26 to seal with the vertical end edges of the sheets 10. Tie rods 28 extend through the spaces between certain sheets 10 and pass through horizontal openings in the plates 26 and gaskets 27. The rods 28 carry heads or nuts 29 which clamp against the outer sides of the plates 26 to hold the gaskets 27 in tight sealing engagement with the end edges of the sheets 10. The gaskets 27 may seal with the opposite ends of the pans 22 to prevent leakage between the pans and the plates 26.

Means are provided to stabilize and hold the banks of sheets 10 of the units A and B. These means include angle irons 30 gasketed to and extending upwardly from the sides 16 of the pans

22 and connected at their upper ends by horizontal bars or angle irons 31. The angle irons 30 and 31 occur at the outer sides of the outermost sheets 10. The angle irons 31 carry upwardly projecting lugs 32 and tie rods 33 connect the lugs 32 at the opposite sides of the sheet banks. The tie rods 33 preferably carry spacers 34 which extend horizontally across the upper edges of the spaced sheets 10. Plates 35 are arranged at the ends of the banks of sheets 10 adjacent the upper ends of the banks and gaskets 36 of rubber, or the like, are provided on the inner sides of the plates 35 to cooperate with and seal against the end edges of the sheets 10. Tie rods 37 are arranged horizontally in the spaces between certain of the sheets 10 and pass through openings in the plates 35 and gaskets 36. Nuts 38 are screwed on the ends of the rods 37 and clamp against the outer sides of the plates 35 so that the gaskets 36 are clamped against the edges of the sheets 10 to seal with the sheets and to assist in stabilizing the sheets. The plates 35 are adjacent the inner edges of the base walls 18.

In accordance with the invention the vertical surfaces 26 of the glass sheets 10 are finished or formed to insure substantially equal distribution of the liquid films. The surfaces 26 are corrugated, being provided with multiplicities of spaced parallel grooves 39. The grooves 39 extend vertically between the upper and lower edges of the sheets 10 and are provided throughout the entire sheet surfaces 26. The grooves 39 preferably have curved walls and are shallow. It is preferred to make the grooves 39 about .015 of an inch deep. The grooves 39 are equally spaced apart and are spaced and formed so that the surfaces 26 have alternate vertical ridges and grooves and, therefore, are, in effect, corrugated. The grooves 39 eliminate the tendency of the liquid to crawl or form lateral streams but are so shallow that the liquid is obliged to spread and cover the entire surfaces 26. The grooves 39 also perform a useful function in cooperation with certain elements of the means 11, as will be later described. Further, the cooperation of the grooved surfaces 26 with the gaskets, etc. assures better sealing engagements and assists in stabilizing the banks of sheets.

The means 11 for supplying the films of water and brine to the surfaces 26 of the sheets 10 is a feature of the invention. The means 11 of each bank or unit A and B includes feed trays 40^b and 40^w arranged at the opposite ends of the bank of sheets 10. The trays 40^b and 40^w are positioned at the above-mentioned plates 35 so that the plates form their inner walls. The inner edges of the trays 40^b and 40^w seal with gaskets 41 on the outer sides of the plates 35. Securing rods 42 clamp the trays inwardly so that their inner edges tightly seal with the gaskets 41. The rods 42 may be associated with the tie rods 37. The upper edges of the trays 40^b and 40^w may be substantially flush with the upper edges of the walls 17 and 18. The ends of the trays 40^b and 40^w may cooperate with the inner surfaces of the walls 17 and 18. The trays 40^b carry brine or other suitable liquid having a lower vapor pressure than water while the trays 40^w carry water. It is to be noted that where the units A and B are arranged in end to end relation and in corresponding positions, the tray 40^w of the unit A is adjacent and in opposing relation to the tray 40^b of the unit B. The trays 40^b and 40^w are supplied with liquid from the sumps 20. Liquid lines 75 or pipes 43 extend from the sumps 20 to the re-

lated trays 40^b and 40^w. Motor driven pump units 44 are connected in the pipes 43 to pump the liquid from the sumps to the trays.

The trays 40^b and 40^w serve to deliver the brine and water to the spaces between the spaced sheets 10. Ports 45 are formed in the plates 35 and the gaskets 36 to connect the interiors of the trays 40^b and 40^w with the spaces between the plates 10. The ports 45 are horizontally spaced so that a given tray 40^b or 40^w communicates with every other space defined by the spaced plates 10. Thus the ports 45 place the sumps 40^b in communication with the spaces 46^b and place the trays 40^w in communication with the spaces 46^w. The spaces 46^b and 46^w are intermeshing, that is, each bank of sheets 10 has or defines a space 46^b, a space 46^w, a space 46^b, and so on.

The liquid supplying or handling means 11 further include control elements or valve elements governing the delivery of the brine and water to the major portions of the sheet surfaces 26 to cover the surfaces with liquid films. The valve elements are in the nature of tubes 47 of rubber or other flexible resilient material arranged horizontally in the several spaces 46^b and 46^w but below the ports 45. The end portions of the tubes 47 pass through openings 48 in the plates 35 to project outwardly from the plates. Headers or manifolds 49 bear against the gaskets 41 of the plates 35 to have their interiors in communication with the tubes 47. Bushings or ferrules 50 are arranged in the portions of the tubes 47 which pass through the openings 48. The external diameter of the ferrules 50 is substantially equal to the normal internal diameter of the tubes 47. The tubes 47 are sealed and secured in the openings 48 in a novel, improved manner. Following the insertion of the ferrule 50 in an end portion of a tube 47 this portion of the tube is put under tension and is stretched or elongated. This elongation is accompanied by reduction in the wall thickness of the tube 47 and the portion of the tube thus reduced in external diameter is passed through an opening 48. The tension is then removed from the tube 47 and the tube expands through its resiliency to have tight sealing cooperation with the wall of the opening 48. The ferrules 50 are formed of rigid material and form internal supports which prevent a reduction in the internal diameter of the tubes when the tubes are set in the openings 48, as described.

The manifolds 49 are held in place by tie rods 51 provided with nuts 52 that clamp the manifolds against the gaskets 41. The tie rods 51 pass through certain of the tubes 47. The other tubes 47 contain rigid rods 53. The rods 51 and 53 are considerably smaller in diameter than the tubes 47 to leave clear annular passages in the tubes. The rods 51 and 53 serve to prevent distortion and sagging of the tubes 47. The liquid from the trays 40^b and 40^w is admitted to the spaces 46^b and 46^w above the tubes 47 and the upper portions of the spaces may contain substantial quantities of the liquid. The rods 51 and 53 serve to support the flexible tubes 47 so that the weight of this liquid does not excessively distort the tubes.

The tubes 47 constitute sealing elements or valve elements for sealing with the surfaces 26 of the sheets. There is a tube 47 provided in each space 46^b and 46^w and the tubes 47 are proportioned so that they normally or initially clear the surfaces 26 or engage but slightly against the surfaces. The invention provides means for inflating the tubes 47 or for subjecting the

tubes 47 to internal pressure so that they are expanded into sealing engagement with the surfaces 26 to control the escape or flow of the liquid from the portions of the spaces 46^b and 46^w above the tubes. One manifold 49 of each unit A and B has a valved connection 54 for admitting fluid under pressure. The fluid under pressure supplied to the manifolds 49 and the tubes 47 expands the tubes to engage and seal against the surfaces 26. By varying the pressure of the fluid admitted to the manifolds 49 the tubes 47 are expanded to a greater or less extent to control the rate of liquid flow down the surfaces 26 of the sheets 10. It is to be noted that all of the valve tubes 47 of a unit A or B are simultaneously expanded or deflated to the same degree by admitting or exhausting the fluid pressure at the fitting 54. The tubes 47 seal against the surfaces 26 to oblige the liquid to run down the grooves 39. The exteriors of the expanded tubes 47 engage the ridges occurring between the grooves 39 and being flexible and formable may partially close the grooves 39. The tubes 47 seal with or engage the surfaces 26 defining the spaces 46^b and 46^w and control the escape or discharge of the brine and water in such a manner that films of the brine and water flow down each surface. It will be observed that the surfaces 26 defining the spaces 26^b carry films of the brine while the surfaces 26 defining the spaces 46^w carry films of water. It is to be further noted that each glass sheet 10 has a film of brine on one surface 26 and a film of water on its other surface 26.

The films of brine and water flowing down the surfaces 26 of the sheets 10 are, of course, stopped by the gasket pads 25 in the pans 22. The liquid flows along the pads 25 to the plates 26, or accumulates in the pans 22. Discharge openings 56 are provided in the plates 26 and their gaskets 27 to communicate with the lower ends of the spaces 46^b and 46^w. The ports 56 are in the same relation as the ports 45 and serve to discharge the liquids from the lower ends of the spaces 46^b and 46^w to the sumps 20 for recirculation to the trays 40^b and 40^w by the pump means 44.

The means 12 operates to circulate the air to be treated through the spaces 46^b of the unit A to be cooled, dried, and de-odorized through contact with the brine films flowing down the surfaces 26 defining said spaces. The means 12 includes a suitable air conduit 57 extending from the compartment or space being conditioned. The conduit 57 has its outer end in communication with the outer end of the unit A. The outer end of the air conduit 57 joins or is received between the walls 18 and is between the tray 40^b and the end sump 20 of the unit A. A longitudinal horizontal partition 58 extends longitudinally through the conduit 57 to divide the conduit into upper and lower passages. Sets of suitable louvers 59 are provided at the outer ends of these passages where they communicate with the space being conditioned. The partition 58 extends to or joins a substantially horizontal shelf 60 arranged between the outer end walls 18 of the unit A. Partition rods 61 extend into the spaces 46^b of the unit A. The rods 61 extend inwardly from the shelf 60 and terminate in a vertical plane spaced some distance from the vertical plane occupied by the inner edges of the sheets 10 of the unit A. The rods 61 may be supported on the shelf 60. In accordance with the invention the rods 61 form horizontal bar-

riers or air deflectors in the spaces 46^b of the unit A.

The air handled by the conduit 57 is prevented from entering the spaces 46^w of the unit A and the air in the spaces 46^w of the unit A is prevented from entering the spaces 46^b. In a similar manner the air circulated through the spaces 46^b and 46^w of the unit B is kept distinct and segregated. The outer ends of the spaces 46^w of the unit A are closed, the inner ends of the spaces 46^b of the unit A are closed, the outer ends of the spaces 46^b of the unit B are closed, and the inner ends of the spaces 46^w of the unit B are closed. The means for closing the said ends of the spaces 46^b and 46^w comprise members 62 of wood or metal arranged against the edges of pairs of adjacent sheets 10. Inner members 63 of rigid material are inserted between the pairs of sheets 10 in spaced adjacent relation to the outer members 62 and vertically disposed tubes 64 of rubber, or the like, are arranged between the opposing members 62 and 63. The tubes 64 are initially cylindrical and formed to rather snugly fit between the opposing surfaces 26 of the sheets 10. Following the assembling of the tubes 64 between the members 62 and 63, the members 63 are moved outwardly toward their related members 62. Screws 65 passing through openings in the members 62 and threaded in openings in the members 63 may be employed to accomplish this movement. Movement of the members 63 toward the members 62 distorts the tubes 64 and this distortion causes the tubes 64 to tightly seal with the surfaces 26 of the sheets 10 to prevent the leakage of liquid and air.

The means 12 for bringing the air to be treated into contact with the brine films of the unit A further includes air moving means. This air moving means may be in the nature of a motor driven fan 66 arranged on the shelf 60. The fan 66 draws air in through the lower passage of the conduit 57 and drives the treated air out through the upper passage of the conduit 57. The air is thus made to circulate through the spaces 46^b of the unit A and is brought into contact with the brine films of these spaces throughout substantially the entire extents of the sheets 10. As will be later described, the brine films act as cooling, drying (condensing) and de-odorizing agents for the air and the sheets 10 serve to conduct heat from the brine films to the water films on their opposite surfaces.

The means 13 operates to continuously circulate a stream of air through the spaces 46^w of the unit A and the spaces 46^b of the unit B. With the closure means 62—63—64 arranged as described above, the inner edges of the spaces 46^w of the unit A are open and directly oppose the open inner ends of the spaces 46^b of the unit B. The means 13 includes partition rods 67 extending into the spaces 46^w of the unit A and the spaces 46^b of the unit B. The rods 67 are substantially horizontal and may lie in the same horizontal planes as the rods 61. For the purpose of illustration Fig. 2 shows the rods 61 and 67 slightly offset. The outer extremities of the rods 67 occur in vertical planes spaced from the planes occupied by the outer edges of the sheets 10 of the units A and B. The means 13 further includes a horizontal partition 68 in the space between the units A and B disposed in substantially the same plane as the rods 67. The partition 68 extends between the side walls 17 of the base and the inner edges of the sheets 10 of the

units A and B. The partition 68 may serve to support the rods 67. Air moving means in the form of a motor driven fan 69 or its equivalent is arranged to circulate air in a continuous path around the partition structure defined by the rods 67 and the partition 68 to flow through the spaces 46^w of the unit A and the spaces 46^b of the unit B. Fig. 1^a illustrates the path of the air circulated by the fan 69.

The means 14 handles outside air and brings this air into contact with the water films of the spaces 46^w of the unit B. The means 14 includes a suitable air conductor or conduit 70 leading to the atmosphere and having its inner end in communication with the spaces 46^w of the unit B. The conduit 70 is connected with or received between the plates 18 of the unit B to communicate with the outer ends of the spaces 46^w between the tray 40^b and the related sump 20. A horizontal partition 71 extends longitudinally through the conduit 70 to divide the conduit into upper and lower passages. Partition rods 72 extend into the spaces 46^w of the unit B and terminate in a vertical plane spaced from the inner edges of the sheets 10. The rods 72 may lie in the same plane as the partition 71. A shelf 73 forming an inner extension of the partition 71 supports the rods 72. A motor driven fan 74 or its equivalent is supported on the shelf 73 to circulate the air through the spaces 46^w and the conduit 70. Fig. 1^a of the drawings illustrates the manner in which the fan 74 circulates the air.

In the operation of the apparatus the fans 66, 69 and 74 are in continuous operation and sufficient supplies of water and brine are maintained in the trays 40^b and 40^w to assure the formation of the brine and liquid films on the surfaces 26 of the plates 10. I prefer to employ a brine solution of calcium chloride, although the "brine" used in the apparatus may be any suitable liquid having a lower vapor pressure than water. It is preferred to maintain the concentration of the brine or solution substantially constant for the efficient operation of the apparatus. As described above, the fan 66 delivers the air to be treated to the unit A and handles it in such a manner that it is made to come into contact with the brine films in the spaces 46^b of the unit A, the fan 69 continuously recirculates a stream of air in such a manner that it passes through the spaces 46^w of the unit A and the spaces 46^b of the unit B and the fan 74 circulates the outside air through the spaces 46^w of the unit B. The action resulting from this circulation of air into contact with the brine and water films is as follows: The outside air brought into contact with the water films in the spaces 46^w of the unit B results in evaporative cooling, causing the temperature of these water films to approach the wet bulb temperature of the atmosphere. By heat conduction through the plates 10 of the unit B the brine films flowing down the surfaces 26 of the spaces 46^b of the unit B also approach the atmospheric wet bulb temperature. The brine films in the spaces 46^b of the unit B have a lower vapor pressure than the water films in the spaces 46^w of the unit A. This relationship results in a heat transference from liquid to air and from air to liquid. The air coming into contact with the brine films in the spaces 46^b of the unit B has previously approached the saturation point through contact with the water films in the spaces 46^w of the unit A and, therefore, has a high latent heat content and a high vapor pressure. The

temperature and the vapor pressure of this air approach those of the brine films in the spaces 46^b of the unit B. The heat flows or travels from the circulating air to the brine films in the spaces 46^b of the unit B. The condensation of the vapor on the brine films of the spaces 46^b of the unit B maintains the temperature of these films above the temperature of the water films in the spaces 46^w of the unit B and there is an appreciable transference of heat through the plates 10 of the unit B. The air leaving the brine films in the spaces 46^b of the unit B has been held at a reasonable temperature and is relatively dry and, therefore, has a low wet bulb. The films in the spaces 46^w of the unit A have a high vapor pressure and heat flows from the water films to the circulating air. By reason of the heat conduction through the plates 10 of the unit A, the temperature of the brine films in the spaces 46^b of that unit approaches the temperature of the water films in the spaces 46^w of the same unit. The air from the space being conditioned coming into contact with the brine films in the spaces 46^b of the unit B is cooled and dried by the same action that takes place when the air contacts the brine films in the spaces 46^b of the unit B. The brine in the spaces 46^b of the unit A in addition to reducing the temperature and moisture content of the air being treated serves to deodorize the air and to a considerable extent absorb particles and impurities. It has been found that the brine films in the spaces 46^b of the unit A are very effective in the removal of undesirable gases from the air and it is believed that passage of the air over the brine films leads to increased ionization of the air.

It will be observed that there is a stage transference of heat through the units A and B and that the units A and B are functionally connected by the heat transferring air circulated by the means 13 so that it flows from the water films of the unit A to the brine films of the unit B and then back again. In actual operation there is a substantial reduction in room temperature and a relative humidity of between 50 and 60 per cent in the room conditioned by the apparatus. The apparatus removes a substantial percentage of foreign matter from the air and by employing a suitable brine it is possible to effectively remove undesirable gases from the air and to increase the ionization of the air.

The rate of action of the apparatus may be controlled or varied by varying the fluid pressure in the valve tubes 47. By suitable manipulation of the valve fittings 54 the fluid pressure in the tubes 47 of either one or both of the units A and B may be lessened to increase the liquid flow down the surfaces 26 of the glass sheets 10. By increasing the fluid pressure in the tubes 47 the liquid flow down the surfaces of the sheets 10 is reduced. The apparatus is quiet and efficient in operation and requires a minimum of servicing. From time to time it may be necessary to flush the apparatus. This may be accomplished by exhausting or relieving the fluid pressure in the tubes 47. This allows liquid from above the tubes 47 to freely discharge down the surfaces 26 of the plates 10 to flush the same. Following this flushing action the tubes 47 may be re-inflated to the selected pressure.

Having described only a typical preferred form and application of my invention, I do not wish to be limited or restricted to the specific details herein set forth, but wish to reserve to myself any variations or modifications that may appear

to those skilled in the art or fall within the scope of the following claims.

Having described my invention, I claim:

1. Apparatus for the transfer of sensible and latent heat comprising two sheets, means providing films of liquid on the opposite surfaces of the sheets, the film on one surface of each sheet having a lower vapor pressure than the film on the other surface, means bringing air into contact with the film of higher vapor pressure on one sheet to produce an evaporative cooling action, means circulating air from the film of lower vapor pressure on said sheet to the film of higher vapor pressure on the other sheet to produce an evaporative cooling action and moving the air back to the film of lower vapor pressure on the first named sheet to provide for a transference of heat, and means bringing the air to be treated into contact with the film of lower vapor pressure on the said other sheet to give up heat and moisture, said sheets transferring heat by conduction.
2. In apparatus for the transfer of sensible and latent heat, a sheet, means for providing a liquid film on one surface of the sheet, means for providing a liquid film of a lower vapor pressure on the other surface of the sheet, means for moving air against the first named film to produce an evaporative cooling action, and means for bringing the air to be treated against the second named film to give up heat and moisture, said sheet conducting heat from said first named film to said second named film, said surfaces of the sheets having a configuration which causes small volumes of the liquids to spread uniformly over the surfaces as self sustained flowing films.
3. Apparatus for the transfer of sensible and latent heat comprising two sheets, means providing films of liquid on the opposite surfaces of the sheets, the film on one surface of each sheet having a lower vapor pressure than the film on the other surface, means bringing air into contact with the film of higher vapor pressure on one sheet to produce an evaporative cooling action, means continuously circulating air between the sheets to move from the film of lower vapor pressure on said sheet where it gives up heat and moisture to the film of higher vapor pressure on the other sheet where it absorbs heat and moisture, and then back to the film of lower vapor pressure on the first named sheet for re-cycling, and means bringing the air to be treated into contact with the film of lower vapor pressure on said other sheet to give up heat and moisture.
4. In apparatus for the transfer of sensible and latent heat, a sheet of glass, means for providing a liquid film on one surface of the sheet, means for providing a liquid film of a lower vapor pressure on the other surface of the sheet, said surfaces of the sheet having alternate grooves and ribs of such shape and depth relative to a drop of the liquid that they cause small volumes of the liquid to spread substantially uniformly over said surfaces as self sustaining flowing films, means for moving air against the first named film to produce an evaporative cooling action, and means for bringing the air to be treated against the second named film to give up heat and moisture, said sheet conducting heat from said first named film to said second named film.
5. Apparatus for the transfer of sensible and latent heat comprising two sheets, means providing films of liquid on the opposite surfaces of the sheets, the film on one surface of each sheet hav-

ing a lower vapor pressure than the film on the other surface, means bringing air into contact with the film of higher vapor pressure on one sheet to produce an evaporative cooling action, means continuously circulating air between the sheets to move from the film of lower vapor pressure on said sheet where it gives up heat and moisture to the film of higher vapor pressure on the other sheet where it absorbs heat and moisture and then back to the film of lower vapor pressure on the first named sheet for re-cycling, and means bringing the air to be treated into contact with the film of lower vapor pressure on said other sheet to give up heat and moisture, said surfaces of the sheets having grooves extending longitudinally of the direction of travel of the films.

6. Apparatus for the transfer of sensible and latent heat comprising at least two generally upright sheets of glass, means for feeding liquid to the opposite surfaces of the sheets to form downwardly flowing films on the surfaces, the liquid of one film of each sheet having a lower vapor pressure than the liquid of the other film, means for bringing air into contact with the film of higher vapor pressure on one of the sheets to bring about a reduction in the temperature of said film by an evaporative action, said sheet conducting heat from its film of lower vapor pressure to its film of higher vapor pressure, means for circulating a stream of air to move from the film of higher vapor pressure on the other sheet to the film of lower vapor pressure on the first named sheet and back to the film of higher vapor pressure on said other sheet to give up heat and moisture through contact with the film of lower vapor pressure on said first named sheet and to have an evaporative cooling action on the film of higher vapor pressure of said other sheet, said other sheet conducting heat from its film of lower vapor pressure to its cooled film of higher vapor pressure, and means for bringing the air to be treated into contact with the film of lower vapor pressure on said other sheet.

7. In apparatus for the transfer of sensible and latent heat two units, each unit comprising a series of horizontally spaced substantially vertical sheets, means for supplying liquid to the upper parts of alternate spaces between the sheets, means for supplying liquid of a lower vapor pressure to the upper parts of the other spaces between the sheets, and means for causing said liquids to run down the surfaces of the sheets in films, the spaces of one unit carrying the liquid of higher vapor pressure being in communication with the spaces of the other unit carrying the liquid of lower vapor pressure, means for circulating air through the said communicating spaces to move from the first named unit into the second named unit and then back into said first named unit, means for moving outside air through the spaces of said other unit carrying the liquid of higher vapor pressure, and means for moving the air to be treated through the spaces of the first named unit carrying the liquid of lower vapor pressure.

8. In apparatus for the transfer of sensible and latent heat, two spaced sheets having opposing grooved surfaces, means for delivering liquid to the space between the sheets, and means for causing the liquid to flow on the opposing surfaces of the sheets as films comprising an inflatable resilient and somewhat conformable tube between the sheets engaging with said

surfaces below the first named means to control the flow of liquid through the grooves.

9. In apparatus for the transfer of sensible and latent heat, two spaced sheets, the opposing surfaces of the sheets having multiplicities of spaced grooves, means for delivering liquid to the space between the sheets, and means for causing the liquid to flow on the opposing surfaces of the sheets as films comprising an inflatable resilient tube between the sheets co-operable with said surfaces.

10. In apparatus for the transfer of sensible and latent heat, a bank of horizontally spaced substantially vertical sheets, means closing the alternate spaces between the sheets at one side of the bank, means closing the other spaces at the other side of the bank, means for supplying liquid to the upper parts of the spaces to flow down the sheets, and means for circulating air through the open sides of the spaces.

11. In apparatus for the transfer of sensible and latent heat, a bank of horizontally spaced substantially vertical sheets, means closing the alternate spaces between the sheets at one side of the bank, means closing the other spaces at the other side of the bank, means for supplying liquid to the upper parts of the spaces to flow down the sheets, substantially horizontal partitions extending into the spaces from their open sides, and means for circulating air through the open sides of the spaces.

12. In apparatus for the transfer of sensible and latent heat, a bank of horizontally spaced substantially vertical sheets, the surfaces of the sheets being grooved, and regulable means for providing films of liquid on the said surfaces comprising a manifold at a side of the bank, expansible tubes extending through the spaces between the sheets and having communication with the manifold, means for admitting fluid under pressure to the manifold to expand the tubes into sealing cooperation with said surfaces, and means for supplying liquid to the spaces above the tubes.

13. In apparatus for the transfer of sensible and latent heat, a bank of horizontally spaced substantially vertical sheets, the surfaces of the sheets being grooved, and regulable means for providing films of liquid on the said surfaces comprising a manifold at each side of the bank having spaced openings, expansible resilient tubes extending horizontally through the spaces between the sheets and having parts of lessened external diameter confined in said openings, tubular ferrules in said parts of the tubes maintaining the internal diameter of the tubes, means for supplying fluid under pressure to the manifolds to expand the tubes against the sheets, and means for delivering liquid to the spaces above the tubes.

14. In apparatus of the character described two spaced generally vertical sheets for exposing films of liquid, the opposing surfaces of the sheets being provided with grooves directed and related in size and shape to a drop of the liquid to cause small volumes of the liquid to be distributed substantially uniformly over said surfaces as self sustaining flowing films, means for delivering the liquid to the space between the sheets, and means for causing the liquid to flow on said surfaces as films comprising an inflatable resilient tube between the sheets engaging said grooved surfaces in a plane below the liquid delivering means.
